MARINE DRIVE UNIT

William H. Van Gorden, Riverside, Conn.

Application September 23, 1943, Serial No. 503,460

7 Claims. (Cl. 115—35)

This invention relates to drives for boats, and it is especially useful for very high speed boats such as Commando boats.

One of the primary objects of the invention is to provide a drive unit which gives greatly increased speeds, can be readily installed and removed, and has a fast "wheel."

How the foregoing, together with such other objects and advantages as may hereinafter appear or are incident to the invention are realized is illustrated in the accompanying drawings, wherein—

Figure 1 is a fragmentary sectional view illustrating the drive unit in a more or less diagrammatic form.

Figure 2 is a plan view of Figure 1.

Figure 3 is an enlarged section illustrating certain details of the invention.

Figure 4 is a plan view of Figure 3.

Figure 5 is a section taken on the line 5—5 of Figure 3.

Figure 6 is a view similar to Figure 1 but drawn on a somewhat enlarged scale.

Figure 7 is a section through the rear end portion of the drive unit, also drawn on an enlarged scale, and

Figure 8 is an enlarged section taken on the line 8—8 of Figure 7.

Referring now to Figure 1, the unit indicated as a whole by the reference character A comprises the thrust tube 7 with ball 8, the bed plate 9 extending forwardly of the ball and carrying the motor 10, the drive shaft 11, and the propeller 12. The ball swivels in the ring indicated as a whole by the reference letter b. This ring is comprised of two complementary yoke members 13 and 14, more clearly shown in Figures 3 to 5 inclusive. The ball has upper and lower pivot pins 15 fitting in sockets in the yoke members which permits the unit to be swung through the steering gear, indicated as a whole by the reference character c and which may be of any conventional type. This makes it possible to dispense with a rudder, as the unit itself functions as a rudder.

The well is closed by the plates 16 and 17.

The forward end of the bed plate 9 rests on the rubber roller or rollers 18 which provide a floating support somewhat similar in action to the support frequently employed for automobile motors.

Packing rings 19 may be provided to prevent leakage past the ball.

Referring now to Figures 6, 7 and 8, it will be seen that the propeller shaft 11 has a taper hexa-

gon 20 at its rear portion and that such portion is surrounded by the sleeve 21 which also has a taper hexagon to receive the hub 22 of the propeller 12. This dispenses with keyways which are out of balance and which, if used with speeds such as I contemplate, would produce heavy vibration.

The propeller is secured by means of the nut 23.

At its forward end the sleeve 21 has a thrust plate 24 which delivers the thrust of the propeller to the thrust bearing 25 which comes up against the solid back 26. Thus the drive shaft is relieved of stress and tends to run with a minimum of vibration which makes for higher R. P. M.'s and higher speeds.

The rounded portion of the sleeve 21 adjacent to the thrust plate 24 runs in the ball bearings 27 which also makes for smooth running and increased speed. Water is excluded from the tube 7 by the stuffing box packing and gland 28.

At suitable spaced points, depending upon the length of the particular unit, there are additional ball bearings 29 and 30 which also make for smooth running, minimum resistance and increased speeds. The propeller shaft is connected to the motor shaft by the coupling 31.

The ring member 6 is secured to the boat as shown in Figure 2.

It will be seen from the foregoing that I have provided a very simple, smooth running unit which can be readily installed and removed and gives a fast "wheel." The pivot point being well forward gives greatly increased pivoting, as contrasted with the ordinary rudder, so that the boat responds to the slightest movement of the steering wheel. The unit is buoyant and, therefore, assists in getting the boat "on top." It will be clear that it is possible to get away from ship or dock very readily even when the wind and tide are adverse. It will also be seen that a maximum of power is delivered to the propeller, and since the rear end of the thrust tube is the same size as the hub to the propeller, solid water delivers to the propeller. To assist in bringing the propeller back to normal, the tube 7 may be provided with fins 32.

The drive or propeller shaft may be made of steel.

The ball socket is a ground-fit normally watertight joint. The bearings may be lubricated in any desired manner as by forced feed with a feed pipe and return pipe leading from each bearing to a suitable source of pressure lubricant. The tube 7 may be arranged to take in cooling

water for the motor. To the rear of the bearing 30 is a water-tight disk 32' to prevent water from entering the boat through the tube 7 in the event that a tube leak develops, as, for example, might happen in case the boat hits something.

I claim:

1. A marine drive unit comprising a propeller and its drive shaft, a tube surrounding said shaft, a ball at the forward end of said tube, a bed secured to and extending forwardly of the ball, a motor on said bed, a ring adapted to be secured to the boat and in which the ball is pivoted or trunnioned, a coupling between the said shaft and the shaft of the motor, bearings for the drive shaft mounted in said tube, and supporting means for supporting the forward end of the bed with freedom for swinging of the unit, said supporting means being yielding.

2. A marine drive unit comprising a propeller and its drive shaft, a tube surrounding said shaft, a ball at the forward end of said tube, a bed secured to and extending forwardly of the ball, a motor on said bed, a ring adapted to be secured to the boat and in which the ball is pivoted or trunnioned, a coupling between the said shaft and the shaft of the motor, bearings for the drive shaft mounted in said tube, and a steering quadrant at the forward end of the bed.

3. A marine drive unit comprising a propeller and its drive shaft, a tube surrounding said shaft, a ball at the forward end of said tube, a bed secured to and extending forwardly of the ball, a motor on said bed, a ring adapted to be secured to the boat and in which the ball is pivoted or trunnioned, a coupling between the said shaft and the shaft of the motor, a sleeve on the aft end of the drive shaft and extending into the tube, said sleeve having a tapered polygonal portion and a circular portion adapted to fit into the hub of the propeller, a thrust bearing within the tube against which the forward end of said sleeve is adapted to bear, bearing means in the tube aft of the thrust bearing, and a stuffing box gland aft of said bearing means.

4. A marine drive unit comprising a propeller and its drive shaft, a tube surrounding said shaft, a ball at the forward end of said tube, a bed secured to and extending forwardly of the ball, a motor on said bed, a ring adapted to be secured to the boat and in which the ball is pivoted or trunnioned, a coupling between the said shaft and the

shaft of the motor, a sleeve on the aft end of the drive shaft and extending into the tube, said sleeve having a tapered polygonal portion and a circular portion adapted to fit into the hub of the propeller, a thrust bearing within the tube against which the forward end of said sleeve is adapted to bear, a ball bearing for the sleeve aft of the thrust bearing, and a stuffing box gland aft of the ball bearing.

5. A marine drive unit comprising a propeller and its drive shaft, a tube surrounding said shaft, a ball at the forward end of said tube, a bed secured to and extending forwardly of the ball, a motor on said bed, a ring adapted to be secured to the boat and in which the ball is pivoted or trunnioned, a coupling between the said shaft and the shaft of the motor, a sleeve on the aft end of the drive shaft and extending into the tube, said sleeve having a tapered polygonal portion and a circular portion adapted to fit into the hub of the propeller, a thrust bearing within the tube against which the forward end of said sleeve is adapted to bear, a ball bearing for the sleeve aft of the thrust bearing, a stuffing box gland aft of the ball bearing, and bearing means for the drive shaft forward of the thrust bearing.

6. A marine drive unit comprising a propeller and its drive shaft, a tube surrounding said shaft, a ball at the forward end of said tube, a bed secured to and extending forwardly of the ball, a motor on said bed, a ring adapted to be secured to the boat and in which the ball is pivoted or trunnioned, a coupling between the said shaft and the shaft of the motor, and bearings for the drive shaft mounted in said tube, said tube having external fin means toward the aft end thereof.

7. The combination with a boat having a well or step a substantial distance forward of the stern, of a drive unit comprising a drive shaft tube having its forward end swiveled in the well and extending rearwardly below the hull and to a point adjacent to the stern, a motor bed attached to the forward end of the tube, a motor carried by said bed and having a shaft, a drive shaft extending through the tube, means for coupling the forward end of the drive shaft with the shaft of the motor, a propeller on the aft end of the drive shaft, bearing means in the tube for the drive shaft, and means for supporting the bed for swinging movement of the unit about its swivel.

WILLIAM H. VAN GORDEN.
